UNITED STATES PATENT OFFICE.

WILLIAM H. MULLINS, OF SALEM, OHIO.

DESIGN FOR A RIDGE-CRESTING.

SPECIFICATION forming part of Design No. 24,248, dated April 23, 1895.

Application filed March 4, 1895. Serial No. 540,528. Term of patent 7 years.

To all whom it may concern:

Be it known that I, WILLIAM H. MULLINS, a citizen of the United States, residing at Salem, in the county of Columbiana and State of Ohio, have invented and produced a new and original Design for Roofing Purposes, of which the following is a description, reference being had to the accompanying drawings, in which—

10 Figure 1 is a perspective view of the cresting. Fig. 2 is a top plan view thereof, and Fig. 3 is a longitudinal central section.

The purpose of this design is the adornment of roofs for buildings, my invention residing in the production of a ridge-cresting, as illustrated, which shall constitute an artistic and appropriate finishing for the better class of ornamental roofs. My cresting, like such roofs, may be made of any suitable material, but is especially designed and intended for use in connection with metallic roofs now in extensive use.

In forming and applying cresting embodying my design to the roof of a building, it is

obvious that the same may be struck up from 25 continuous sheets of metal.

The numeral 1, indicates the ridge-cresting, consisting of overlapping stretchers each ornamented by a projecting crocket 2 of a bold horn-like appearance, having for its cross section a double ogee terminating in side fillets 3, the latter ending in small volutes 4, as shown.

This being the substance of my design it will be seen to constitute an attractive and effective closure for the apex of a roof, presenting a new design.

Having thus described my invention, what I claim is—

The design for an ornamented ridge-cresting, substantially as herein shown and described.

In testimony whereof I subscribe my signature in presence of two witnesses.

WILLIAM H. MULLINS.
